(57) **CLAIM**

The ornamental design for a wiper blade, as shown and described.

DESCRIPTION

Cross reference is made to copending U.S. design patent application Ser. No. 29/609,870 entitled "Wiper Blade" by Godelieve Kraemer, which was filed on even date herewith; and U.S. design patent application Ser. No. 29/609,873 entitled "Wiper Blade" by Godelieve Kraemer, which was filed on even date herewith.

FIG. 1 is a perspective view of a wiper blade showing my new design;

FIG. 2 is a right side elevational view of the wiper blade of FIG. 1;

FIG. 3 is a left side elevational view of the wiper blade of FIG. 1;

FIG. 4 is a bottom plan view of the wiper blade of FIG. 1;

FIG. 5 is a top plan view of the wiper blade of FIG. 1;

FIG. 6 is a front elevational view of the wiper blade of FIG. 1; and,

FIG. 7 is a rear elevational view of the wiper blade of FIG. 1.

The broken lines shown in the drawings illustrate portions of the wiper blade that form no part of the claimed design.
